BELL BOOT FOR HORSES

Edward S. Schwartz and Lerton V. Dawson,
Excelsior Springs, Mo.

Application March 5, 1948, Serial No. 13,164

4 Claims. (Cl. 54—82)

1

Our invention relates to bell boots for horses, and more particularly to such boots as are known as half-boots and three-quarter boots. Such boots are well known and comprise a top leather section or bell, a leather bottom section or quarter, a flexible leather strap hingedly connecting the bell and quarter together at the rear of the horse's hoof, and a lug or frog carried by the quarter and seatable in the fourchette of the horse's hoof to maintain the boot properly positioned relative to the hoof.

It is an object of our invention to provide an improved bell boot for horses.

A further object is to provide an improved bell boot for horses which includes novel means for connecting the bell and quarter together.

A further object is to provide an improved bell boot such as that last described which connecting means includes a lower end formed to provide a fourchette-engaging frog.

A further object is to provide an improved bell boot such as that last described wherein said connecting means comprises a single strip of flexible plastic.

A further object is to provide an improved bell boot which includes novel means for weighting the boot.

Other objects and advantages reside in the particular structure of the invention and of the several parts thereof together with the novel combinations and sub-combinations as will be readily apparent to those skilled in the art upon reference to the attached drawing in connection with the following specification, wherein the invention is shown, described and claimed.

In the drawing:

Figure 1 is a longitudinal vertical section through a preferred form of the invention, showing the same applied to a horse's hoof, the hoof being shown in broken lines;

Figure 2 is a rear view thereof;

Figure 3 is a bottom plan view thereof;

Figure 4 is a substantially horizontal section taken substantially on the plane of the line 4—4 of Figure 1;

Figure 5 is an elevation of a detail of a modified form of the invention apart from the rest of the structure;

Figure 6 is a longitudinal vertical section taken substantially on the plane of the line 6—6 of Figure 5, but showing the detail connected to the supporting structure.

Referring specifically to the drawing, wherein like reference characters have been used throughout the several views to designate like

2

parts, and referring more specifically to Figures 1, 2 and 3, 10 designates a horse's hoof having a shoe 11 applied thereto. The hoof includes the usual bulbs, the bulbs 12 located below the pastern which in turn is immediately below the fetlock 14 and ankle 15. Intermediate the bulbs 12 at the back of the hoof there is provided a groove 16 which runs into the frog or fourchette of the hoof. The device according to our invention comprises a lower section or quarter generally designated by 17, and an upper section or bell, generally designated by 18. The upper section or bell 18 comprises an outer domed shell 19 of any suitable material, such as heavy leather, which is provided with a lining 20 of relatively soft material, such as soft leather. The upper edge of the lining is doubled, as at 21, and overlies the upper free edge of the bell to protect the horse's ankle from chafing. The shell 19 terminates on opposite sides of the forward portions of the horse's ankle, and the free ends are connected together by any suitable strap 22 which extends around the leg above the coronet or hairline of the hoof. Any suitable buckle 25 may be utilized to connect the strap 22 to the shell 19.

The lower edge of the lining 20 is connected to the shell 19 by a line of stitching 24, which, at the rear central portion thereof, is upwardly and downwardly directed, as at 23, to provide a substantially inverted V-shaped line of stitching. At this point, the inverted V-shaped line of stitching 23 extends through the upper end of a flexible strap or strip 25 which serves as a hinge for connecting the bell 18 to the quarter 17. The hinge line of the strap 25 comprises the extension of the line of stitching 24 across the legs of the V-shaped section 23. However, stitching has been deliberately avoided along the hinge line for the reason that a continued flexing of the material at this point tends to break away the material intermediate the holes provided for the stitching, whereby to cause rapid deterioration of the hinge and failure of the boot as a whole. By providing the fastening for the upper end of the strap 25 with lines of stitching which intersect the hinge line at like angles, the flexing of the material is in angular relation to the stitching comprising the connection, whereby such stitching is not flexed in use. Thus, there is no cracking of the material along the inverted V-shaped line of stitching 23 in use, whereby the hinge has relatively greater longevity in use. Obviously, the line of stitching 23 could be of other forms than inverted V-shape,

but we have found that this is very convenient in use in that it permits the combined line of stitching 23 and 24 to be a single continuous line, whereby the combined line of stitching may be applied in a single operation.

The quarter 17 is best seen in Figure 4, and comprises a substantially U-shaped strap-like element or section which is adapted to overlie the lower rear portions of the hoof and extend forwardly along the sides or quarters thereof. The quarter comprises a plurality of plies of material, such as the outer ply 26, and the inner ply 28, which are coextensive. Between such plies we have provided an intermediate ply 27 which is formed of suitable weight-providing material, such as soft lead. The ply 27 of lead or the like is not as long as the other plies, as is clearly seen in Figure 4. In obtaining the correct action in a horse using a boot such as this, we have found that it is necessary frequently to weight one hoof of the horse more than another. Consequently, the weight plies 27 may be of varying thicknesses and consequently varying weights to achieve the best results. By providing a built-in weight of this type, the same is unnoticeable and the weight is evenly distributed around the sides and rear portion of the horse's hoof, and at the same time is virtually unnoticeable. The weight ply 27 is secured in place by the stitchings securing the outer and liner plies 26 and 28, respectively, together. The lower end of the hinge-providing strap 25 extends downwardly across the face of the liner ply 28 and has attached thereto or formed thereon a frog 29 which is shaped to fit into the groove 16 or fourchette of the horse's hoof. This structure is covered by a frog cover 30 which comprises a strip of suitable flexible material such as leather. All of the elements just recited, including the plies 26, 27 and 28, together with the lower end of the strap 25, the frog 29 and frog cover 30, are secured together by lines of stitching 31 and 32, Figure 1. One end of the quarter 17 has secured thereto in any suitable manner, as by stitching, a loop 33 of leather or the like. The loop 33 is secured about the straight side of a D-ring 34. The opposite end of the quarter 17 has stitched thereto one end 35 of a leather strap for securing the two ends of the quarter together. A keeper 36 is secured to the quarter 17 forwardly of the end 35 of the strap and inwardly of the adjacent free end of the quarter. Forwardly of the keeper 36, the outer ply 26 of the quarter is provided with transverse spaced slots 37 through which the strap 38 is extended. The strap 38 is extended through the D-ring 34 and back through a buckle 39 which is loose on the strap 38, but confined from longitudinal movement thereon by the adjacent slot 37 and keeper 36 between which the buckle is positioned, Figure 4. The tag end 40 of the strap 38 is provided with the usual belt tongue-receiving holes 41 for securing the belt in an adjusted relation. By locating the buckle 49 loosely on the strap 38, we have found that the strap can be tightened over and over again without placing any undue strain on the stitching securing the end 35 of the strap to the quarter 17.

By providing the lower end of the hinge-providing strap 25 with the frog 29, we have found that the frog may be tailored to fit the groove 16 of any horse's hoof without materially modifying the rest of the boot. The frog cover 30 provides a smooth anti-chafing surface for the hoof and adapts itself to frogs of different sizes and conformation.

In Figures 5 and 6, we have illustrated a modified form of hinge-providing strap, and also a modified bell. In this form of the invention, the bell 50, Figure 6, is formed of flexible plastic material, such as Vinylite, or other suitable plastic, which has the required flexibility. In like manner, the hinge-providing strap or strip 51 is likewise formed of a flexible plastic, such as Vinylite, and the lower end thereof is formed to provide an integral frog 52 which is molded thereon in the manufacture thereof. As in the first-described form of invention, the bell 50 and strap 51 are secured together by a line of stitching 53 which intersects the hinge line at an angle thereto. We have found that the use of a flexible plastic, such as Vinylite, eliminates the rotting of the parts and renders the boot extremely long-lasting in use. The parts are assembled in the same manner shown in Figure 1 and Figure 4, with the quarter 17. Obviously, by forming the hinge-providing strap 51 of plastic, it is an easy matter to mold the frog 52 thereof in any desired shape to fit any particular hoof.

While we have shown and described what is now thought to be the preferred embodiments of the invention, it is to be understood that the same is susceptible of other forms and expressions. Consequently, we do not limit ourselves to the precise structure shown and described hereinabove, except as hereinafter claimed.

We claim:

1. A bell boot for horses, comprising a bell, a quarter, means hingedly connecting said quarter and bell together, said means comprising a flexible strap having upper and lower ends, means connecting said lower end of said strap to said quarter, and an inverted V-shaped line of stitching connecting said upper end of said strap to said bell.
2. A bell boot for horses, comprising a bell, a quarter, means hingedly connecting said quarter and bell together, said means comprising a flexible strap having upper and lower ends, means connecting said lower end of said strap to said quarter, means connecting said upper end of said strap to said bell to provide an intermediate hinge line extending transversely of said strap, said last-named means comprising lines of stitching intersecting said hinge line at like angles.
3. A bell boot for horses, comprising a bell, a quarter, means hingedly connecting said quarter and bell together, said means comprising a flexible strap having upper and lower ends, said quarter comprising a plurality of plies of sheet material, said lower end of said strap being interposed between adjacent plies of said material, and said lower end of said strap being formed to provide a fourchette-engaging frog, one of said plies comprising a sheet of soft metal providing a weight for said quarter, and lines of stitching connecting said plies and said lower end of said strap together.
4. A bell boot for horses, comprising a bell, a quarter, means hingedly connecting said quarter and bell together, said means comprising a flexible strap having upper and lower ends, said quarter comprising a plurality of plies of sheet material, said lower end of said strap being interposed between adjacent plies of said material, and said lower end of said strap being formed to provide a fourchette-engaging frog, one of said plies comprising a sheet of soft metal providing a weight for said quarter, lines of stitching connecting said plies and said lower end of said strap together, and an inverted V-shaped line of stitching

ing connecting said upper end of said strap to
said bell.
